UNITED STATES PATENT OFFICE.

BENOIST S. REDD, OF NEW YORK, N. Y., ASSIGNOR TO R. HOE AND CO., OF NEW YORK,
N. Y., A CORPORATION OF NEW YORK.

AUTOMATIC FEED FOR PRESSES AND THE LIKE.

1,123,594.

Specification of Letters Patent.

Patented Jan. 5, 1915.

Application filed May 18, 1911. Serial No. 623,024.

To all whom it may concern:

Be it known that I, BENOIST S. REDD, a citizen of the United States, residing at New York, county of New York, and State 5 of New York, have invented certain new and useful Improvements in Automatic Feeds for Presses and the like, fully described and represented in the following specification and the accompanying drawings, forming a part of the same.

This invention relates to improvements in automatic feeds for presses and the like.

In presses employing automatic feeds, and more particularly in those employed in connection with electrotype work, it is desirable that the feeding devices be not only rapid in operation but that they should start and complete their movement easily and without shock or jar. It will be understood that in 15 presses used in electrotype work, the forms and wax cases are placed in contact and the two then fed into the press. If the feeding movement starts or finishes the feeding operation abruptly, the relative position of 20 the form and wax case is liable to be changed and any slight shift between these parts may scratch or mar the surface of the wax and thus interfere with obtaining a proper impression.

The present invention has for its object 25 to produce an improved feeding mechanism for presses and the like which is compact, cheap in construction and simple in operation, and in which an easy stopping and starting of the feeding mechanism is obtained.

With this and other objects not specifically referred to in view, the invention consists 30 in certain constructions, and in certain parts, improvements and combinations as will be hereinafter fully described and then specifically pointed out.

Referring to the accompanying drawings: 35 Figure 1 is a plan view of a feeding mechanism embodying the invention, the press platen being indicated in this figure. Fig. 2 is a view similar to Fig. 1 but showing the parts in a different position. Fig. 3 is a front elevation of the construction shown in 40 Fig. 1. Fig. 4 is a side elevation, partly in section, of the construction shown in Fig. 1. Figs. 5 and 6 are detail views.

Referring to the drawings which illustrate one embodiment of the invention, 45 50 55 1 indicates a press platen upon which the

work is fed, this platen being operated in any suitable way, as, for instance, by hydraulic mechanism. The press head will be carried on uprights 2, as usual in such constructions.

Mechanisms embodying the invention will include a carrier on which the work is placed, which carrier may be of any suitable construction. As shown, this carrier consists of a plate 3 sliding on ways 4 supported 60 on arms or brackets 5 extending from the press platen. One of these brackets may support a pocket or trough 5' which is used to contain tools, or for other similar purposes. The operating devices by which the 65 carrier is moved onto and off the press platen will include a crank which may be mounted and operated in various ways. In the particular construction illustrated, this crank (marked 6) is carried on a vertical shaft 7 70 mounted in a bearing 8 formed in a web or brace 9 extending across between the arms 5. This shaft carries at its lower end a gear 10. 75

The power transmitting connections between the crank and the carrier may be varied in form, but in the best constructions 80 will be so arranged as to engage the carrier centrally between the ways or guides on which it moves, as by this construction the strains developed in the operation of moving 85 the carrier will be equally distributed and any tendency of the carrier to bind in its bearings will be overcome. In the particular construction illustrated, the power transmitting connections include a floating lever 90 95 11 pivoted at 12 to the underside of the carrier. As shown, this lever is also pivoted to the crank at 13, this pivotal point being substantially midway between the ends of the lever. Where the power transmitting 100 connections are of the type described, means should be provided for controlling the floating lever. In the particular construction illustrated, the floating lever is controlled by a two-part controlling guide, the two 105 parts of the guide lying on opposite sides of the shaft 7. As shown, this two-part guide consists of slotted brackets 14 which may be cast on the arms 5. The end of the lever upon which this controlling guide operates is provided with a roller 15.

Referring to the construction so far described, and assuming that the parts are in the position shown in Fig. 1, and that the gear 10 is rotated in the direction of the 110

arrow in that figure, it will be seen that as the crank starts its movement, the roll 15 will be caused to engage the right hand member of the controlling guide 14. As the 5 roll 15 passes into the slot of the guide the guide acts as a fulcrum and the lever will cause the carrier to travel from the position shown in Fig. 1 toward the press platen. The carrier will continue to move toward 10 the press platen until the crank has made a half revolution at which time the roller 15 will have traversed the length of the slot in the guide member with which it is engaged and back again and will be occupying a position between the two members of the 15 guide. At this time, also, the pivotal point 12 will occupy a position corresponding to that shown in Fig. 1, but will be between the shaft 7 and the press platen, or, in other 20 words, the carrier will have completed its inward feeding movement. If now, the rotation of the crank be resumed, the roller 15 will pass into the other member of the two-part guide and the travel of the carrier will 25 be resumed in the opposite direction, this travel continuing until the crank has completed another half revolution.

The means for operating the gear 10, when a gear is employed for operating the 30 crank, may be varied. In the particular construction shown, this gear 10 is a worm gear and is arranged to be engaged by a worm 16 on a worm shaft 17, this shaft being supported in a bearing 18 formed in a 35 link 19 and in a bearing 20 formed on a bracket 21. The link 19 is supported by a pivot 22 extending from an ear 23 formed on the web 9 before referred to. The bracket 21 is swiveled on a vertical pivot 40 24 passing through a bearing in a bracket 25 secured to the platen 1. The outer end of the shaft is formed to provide a handle 26 and it is apparent that by grasping the handle the operator may move the shaft so 45 as to bring the worm 16 into or out of engagement with the worm gear 10. The worm shaft 17, when this form of driving mechanism is employed, may be operated by any suitable mechanism. In the particular 50 construction shown, the shaft is provided with a sprocket 27 driven by a chain 28 passing around a sprocket 29 on a driven shaft 30 supported on the frame of the press.

55 In the best constructions embodying the invention means will be provided for automatically throwing out the driving mechanism for the crank at the end of the feeding stroke of the carrier which, in the best construction, will be after the crank has made a half revolution. While these means may be varied, in the particular construction illustrated the link 19 has pivoted to it at 60 31 a latch 32, this latch being arranged to 65 take over a pin 33 extending from the web

9. The outer end of the latch is provided with a roll 34 arranged to be struck by cams 35 arranged opposite each other on the worm gear 10. The latch 32 has a short arm 36 extending below its pivot and to this 70 arm is connected a spring 37 which is also connected to the web 9. As the operator swings the worm into engagement with the worm gear, the latch 32 engages the pin 33 and holds the worm gear and worm in engagement until the worm wheel has made a half revolution at which time the roll 34 is struck by one of the cams 35 and the latch is disengaged from the pin. As soon as the latch is disengaged from the pin the spring 75 37 swings the link 19 over, thus moving the worm out of engagement with the worm wheel.

It will be seen that the feeding device which has been described is simple and certain in operation, is compact and cheap in construction, and that by reason of the crank mechanism and connections, the starting and stopping of the carrier is effected very easily. Furthermore, inasmuch as the 85 power transmitting connections always operate centrally of the carriage, there is no tendency of the carriage to bind in its bearings and the strains on the mechanism are evenly distributed. 90

95 Changes and variations may be made in the construction by which the invention claimed is carried into effect. The invention claimed, therefore, is not to be confined to the particular construction herein described and illustrated in the accompanying drawings.

100 What is claimed is:—

1. In a feeding device for presses and the like the combination with a carrier, of guides therefor, a crank, power transmitting connections between the crank and the carrier, said connections engaging the carrier centrally between the guides, means for rotating the crank, and means for automatically 105 stopping the rotation of the crank at the end of the feeding movement.

2. In a feeding device for presses and the like, the combination with a carrier, of guides therefor, a crank, means for rotating the crank always in the same direction, power transmitting connections between the crank and the carrier, said connections engaging the carrier centrally between its guides, and means for automatically stopping the rotation of the crank at the end of each half revolution. 110

115 3. In a feeding device for presses and the like, the combination with a carrier, of guides therefor, a crank, means for rotating the crank always in the same direction, an actuating lever between the crank and the carrier, and means for stopping the rotation of the crank at the end of the feeding stroke 120 of the lever. 130

4. In a feeding device for presses and the like, the combination with a carrier table arranged to support work on the surface thereof, of guides therefor, a crank, means for rotating the crank always in the same direction, a floating actuating lever between the crank and the carrier, said lever having a fixed fulcrum on the carrier, and a controlling guide for the lever.
- 10 5. In a feeding device for presses and the like, the combination with a carrier, of guides therefor, a crank, means for driving the crank always in the same direction, a floating actuating lever between the crank and the carrier, said lever having a fixed fulcrum on the carrier, and a two-part controlling guide for the lever, the parts of the guide lying on opposite sides of the center of rotation of the crank, and means for automatically stopping the rotation of the crank at the end of each half revolution.
- 15 6. In a feeding device for presses and the like, the combination with a carrier, of guides therefor, a crank, means for driving the crank always in the same direction, a floating actuating lever between the crank and the carrier, said lever having a fixed fulcrum on the carrier, and a two-part controlling guide for the lever, the parts of the guide lying on opposite sides of the center of rotation of the crank.
- 20 7. In a feeding device for presses and the like, the combination with a carrier, of guides therefor, a crank, means for driving the crank always in the same direction, a floating actuating lever between the crank and the carrier, said lever being attached to the carrier centrally between the guides, and a two-part controlling guide for the lever, the parts of the guide lying on opposite sides of the center of rotation of the crank.
- 25 8. In a feeding device for presses and the like, the combination with a carrier, of guides therefor, a crank, a worm wheel for actuating the crank, a movable worm for driving the wheel in the same direction, a floating actuating lever between the crank and the carrier, a two-part controlling guide for the actuating lever, and means controlled by the worm wheel for automatically disengaging the worm when the crank has made a half revolution.
- 30 9. In a feeding device for presses and

the like, the combination with a carrier, of guides therefor, a crank, means for rotating the crank always in the same direction, a floating actuating lever between the crank and the carrier, said lever being attached to the carrier centrally between the guides, a two-part slotted controlling guide for the lever, the parts of said guide lying on opposite sides of the center of rotation of the crank, and means for automatically stopping the rotation of the crank at the end of each half revolution.

10 10. In a feeding device for presses and the like, the combination with a carrier, of guides therefor, a crank, a worm wheel for actuating the crank, a movable worm for driving the wheel in the same direction, a floating actuating lever between the crank and the carrier, a two-part controlling guide for the actuating lever, and means controlled by the worm wheel for automatically disengaging the worm when the crank has made a half revolution.

In testimony whereof, I have hereunto set my hand, in the presence of two subscribing witnesses.

BENOIST S. REDD.
